DESIGN FOR AN EGG OPENER AND DIVIDER
OR SIMILAR ARTICLE

Victor E. Murray, Cincinnati, Ohio, assignor of
three-fifths to W. O. Mashburn, Jr., and one-
fifth to Robert Adair Black, both of Cincinnati,
Ohio

Application February 15, 1947, Serial No. 136,924

Term of patent 14 years

(Cl. D44—29)

To all whom it may concern:

Be it known that I, Victor E. Murray, a citizen of the United States and a resident of Cincinnati, in the county of Hamilton and State of Ohio, have invented a new, original, and ornamental Design for an Egg Opener and Divider or Similar Article, of which the following is a specification, reference being made to the accompanying drawing, forming a part thereof.

Fig. 1 is a side elevational view of an egg opener and divider or similar article showing my new design.

Fig. 2 is a side elevational view of the device of Fig. 1, viewed at an angle of 90° from the showing in Fig. 1.

Fig. 3 is a bottom plan view of the egg opener.

Fig. 4 is a top plan view of the egg opener.

Fig. 5 is a view taken on line 5—5 of Fig. 1.

Fig. 6 is a view taken on line 6—6 of Fig. 2.

I claim:

The ornamental design for an egg opener and divider or similar article, as shown.

VICTOR E. MURRAY.
